POCKET SEAL PRESS

Charles Priesmeyer, Park Ridge, Ill., assignor to
Gustav A. J. Meyer, Chicago, Ill.

Refiled for abandoned application Serial No.
199,675, April 2, 1938. This application Decem-
ber 4, 1939, Serial No. 307,384

8 Claims. (Cl. 101—3)

This application is a refiling of my application No. 199,675, filed April 2, 1938.

My invention relates to improvements in pocket type seal presses (such as that shown in my Patent No. 2,077,853 of April 20, 1937) in which the upper die can be depressed by moving a lever in which a roller is journaled, and in which this upper die is supported and normally raised by an approximately horizontal spring part.

10 In such a seal press it has heretofore been customary to provide the upper die with a cylindrical riser stem extending upwards through a perforation in this spring part; also, to employ a cap fitted tightly over the upwardly projecting part of this riser and seated on the spring for supporting the die, upon the top of which cap the roller travels during the depressing of the lever.

In general, the objects of my invention comprise the providing of simple and inexpensive 20 means for overcoming the following shortcomings of the above recited customary assembly of the forward portion of the spring with the upper die and the cap-like pressure-transmitting member.

25 (1) When the riser stem and the corresponding perforation in the spring are both of circular section, the assembler has to be careful when there are markings on both the die and the spring, to insert the said riser stem through 30 the perforation in the spring in exactly the needed rotational position, with respect to the medial vertical and longitudinal plane of the frame of the press, so that an impression made by a reasonably careful user will not be skewed on the sheet. When the cap-like shoe, which must be provided with an upwardly extending bore snugly fitting the said riser stem, is then forced down over that stem, this operation in itself is apt to 35 rotate the stem somewhat, so that each of the just recited assembly steps may cause an undesirably skewed impression of the seal.

40 (2) Whenever the just recited inaccuracy occurs, the cap-like shoe, which must seat on the spring for rigidly clamping the upper die to the spring, has to be pried upwardly somewhat away from the spring before that die can be rotated to correct the error. This in itself means a careful operation, and a further rotational shifting is apt to occur later on when the cap-like shoe 45 is again pressed downward to seat it on the spring.

(3) To insure a rigid supporting of the upper die by a cap thus pressed over the riser stem of that die, it is also necessary to have that stem 50 project to the considerable height required for

alining the bore of the cap with the stem part housed by that bore above the spring, and the thickness of the cap top (which should be imperforate to avoid causing undue wear on the roller) further adds to the space which must be provided between the top of the spring and the roller. Consequently, the height of the frame of the press must be correspondingly large, thereby preventing the press from having the compactness desired for a pocket appliance. 10

(4) In making an impression of a notarial seal on documents it is usually desirable to have the impressed lettering upright on the document. However, different classes of documents vary as to the edge of the sheet near which a space for such an impression is provided, which space may be adjacent to the top, bottom, or either side of the sheet. Consequently, when a notary who mainly certifies only a certain class of documents orders a seal press, he must specify near which 20 of the four edges of the sheet the impression is to be made, so that the seal press manufacturer in each case can mount the dies according to the specifying order, namely in a certain one of four rotationally different positions on the press. 25

(5) Moreover, when the stem-gripping cap has the usual cylindrical exterior which can be most economically manufactured, this cap presents a circular top, so that a roller corresponding in length to the diameter of that top will only bear 30 for its entire length on this top during a small portion of its travel, thereby causing uneven wear.

Illustrative of the simple and inexpensive manner in which my present invention alleviates all 35 of the above difficulties,

Fig. 1 is a central, vertical and longitudinal section through a seal press of the type of my aforesaid patent, including my novel assemblage of the spring with both the lower die and a generally flat pressure-transmitting shoe, showing the parts as they appear when the lever is depressed for making an impression, namely in what I am hereafter calling their "normal" positions. 40

Fig. 2 is a fragmentary horizontal section taken just below the roller which pressed against the shoe, namely along the line 2—2 of Fig. 1.

Fig. 3 is an enlarged section taken along the line 3—3 of Fig. 2 through the lower die, the forward portion of the spring, and the shoe. 50

Fig. 4 is a plan view showing the assembly of the lower die with the forward portion of the spring, before the shoe is placed in its operative 55

position, drawn on the same scale as Figs. 1 and 2.

Fig. 5 is a perspective view of the upper die alone, showing the square-sectioned riser integral with that die.

Fig. 6 is a plan view of the digitally attachable and detachable shoe, drawn on the same scale as Fig. 3.

Fig. 7 is a bottom view of the shoe, showing the recess into which the upper end of the riser on the upper die can project freely.

Fig. 8 is a plan view of the forward portion of the spring alone, showing the square perforation for interchangeably receiving the riser stem of the upper die in any one of the usual four rotationally different positions, and also the auxiliary perforations for receiving the depending fingers on the shoe.

Fig. 9 is a section allied to Fig. 1, but showing the heretofore customary assemblages of a spring with a lower die and shoe, for comparison with my here presented construction.

In carrying out my present invention, I provide the forward part of the spring with a perforation disposed so as to be coaxial with the lower die L when the upper die U and the spring are depressed, but make this perforation P an accurate square having two opposite sides parallel to the medial longitudinal and vertical plane S of the frame F of the press and the spring S, namely parallel to the plane along which the section of Fig. 1 was taken.

Next, I make the axial riser R on the upper die U of a square section slidably fitting the bore of the said perforation P and only slightly taller than the thickness of the flat spring strip S, so that the upper end of this riser will project only to a trivial extent above the spring when this riser has been slid upwards through the said perforation to have the spring seat on the top of the upper die. With such a trivial height of the upwardly projecting riser part, a few light taps on the upper end of the riser with a peening hammer will readily expand the upper edge portion of the riser to wedge the riser in the said perforation for firmly supporting the upper die with two sides of the riser parallel to and equally spaced from the said vertical plane of the press frame.

Then, instead of employing a presser-distributing shoe in the form of a cap C driven tightly down over a tall cylindrical riser R' according to the previous practice (as illustrated in Fig. 9) I use a shoe I detachably seated on the spring and out of all contact with my square-sectioned riser, and provide this shoe and the spring with interengaging formations for definitely positioning the shoe.

Thus, Figs. 3, 6 and 7 show a suitable shoe in the form of a generally flat and rectangular-punching, desirably of steel, which punching has fingers F projecting and depending from opposite ends of its main rectangular part. To co-operate with these fingers I provide the spring with two auxiliary perforations 2, disposed at opposite sides of the aforesaid square perforation P and formed for slidably receiving and interlocking respectively with the said fingers.

Since the interior spread of the lever 3 which carries the pressure exerting roller 4 (Fig. 1) is usually narrow, I preferably space the said auxiliary perforations of the spring longitudinally of the press. This enables me to make the main or rectangular part of the shoe of a width equal to the length of the roller 4, namely a length

closely approximating the interior width of the usual (inverted U-sectioned) lever, so that the roller can bear for its entire length on this shoe at all times.

Moreover, I provide the shoe I with a central bottom recess 8 of greater area than the cross-section of the riser R on the upper die, and of sufficient depth so that the recess bottom will freely clear the top of that riser even when the upper portion of that riser has been peened somewhat for wedging the riser in the square spring perforation. Thus formed, as shown in Figs. 3 and 7, the main rectangular part of the shoe has a flat frame-like lower face, corresponding in spread to the top of shoe, for distributing the downward pressure from the roller 4 of the press over a similarly large area of the spring, namely an area much larger than that afforded by the heretofore employed cap-shaped type of shoe.

Since the square perforation P in the spring readily can be punched accurately as to its size and shape, and the riser R on the upper die also can speedily be shaped accurately by a simple milling machine operation, my present construction permits a speedy and accurate assembling of the spring and the die, with the latter in any one of the usual four alternative rotational positions. Moreover, if another die is to be substituted, or if the die in an assembled press is to be positioned, the press manufacturer (or any fair mechanic employed by a distributor) can speedily release the said riser from the spring by slight lateral taps on the peened stem portions after the shoe has been lifted off the spring.

By employing my above recited accurately fitting and definitely positioned square-sectioned provisions, I also eliminate the heretofore unavoidable extra time required for accurately positioning the upper die. Moreover, I reduce the cost of the press because of the cheapness of my speedily punched shoe in proportion to an accurately bored cap, in addition to reducing the needed height of the frame.

However, while I have heretofore described my invention in connection with an embodiment in which the shoe is definitely positioned by providing it with fingers depending into correspondingly formed perforations in the spring, it is to be understood that this embodiment is merely illustrative, since many changes might be made both as to the shoe-positioning and otherwise, without departing either from the spirit of my invention or from the appended claims.

For example, if the dies are to be used for embossing an ornament which might present a changed appearance in different positions, both the riser of the upper die and the perforation in the spring might be of a different polygonal shape than a square one, provided that this shape also presents sides of equal length disposed at equal consecutive angles.

I claim as my invention:

1. In a seal press of the class in which the upper die underlies and is supported by a flat and normally horizontal spring portion and in which the die is forced downward by a depressing movement of a roller which is movably supported above the spring, a spring having the said portion provided with a square perforation co-axial with the die, the die having a square riser stem extending upwardly into and wedged in the said perforation; and a generally flat pressure transmitting shoe provided with a bottom recess and having a flat frame-like bottom portion extending around the said recess and seated on the

spring; the recess being of larger area than the said perforation and freely housing any portion of the said riser stem which extends above the spring, the shoe being detachably interlocked with portions of the spring to prevent a horizontal shifting of the shoe with respect to the spring.

5. In a seal press, an assemblage of a spring with the upper die of the press and with a shoe, as per claim 1, in which the said square perforation has two opposite sides disposed parallel to the longitudinal axis of the spring; in which the spring has a plurality of formations, near to but spaced from the said square perforation, which formations engage portions of the shoe to afford 10 the said detachable interlocking.

6. In a seal press, an assemblage of a spring with the upper die of the press and with a shoe, as per claim 2, in which the said square perforation has two opposite sides disposed parallel to the longitudinal axis of the spring; in which the spring has a plurality of formations, near to but spaced from the said square perforation, which formations engage portions of the shoe to afford 15 the said detachable interlocking; the shoe being rectangular, disposed with its longer axis in a vertical plane along the longitudinal axis of the spring, and provided at each end of the shoe with a finger; and the spring having two formations respectively in engagement with 20 the said fingers for affording the said interlocking.

7. In a seal press of the class in which a lower die is rigidly supported by a body member, and in which the impression is effected by movement 25 of a lever which is pivoted in the body member, a spring fastened to the body member and having a flat and approximately horizontal movable spring portion extending above and across the axis of the lower die, the said spring having a 30 perforation co-axial with the said die axis; an upper die underlying the said spring portion and having a riser stem firmly socketed in the said perforation, a shoe seated upon and detachably interlocked with the said spring portion and 35 freely overlying the said riser stem, and a roller journaled on the lever on a horizontal axis parallel to the pivot axis of the lever; the shoe 40 having a flat top parallel to the top of the said spring portion, the roller being continuously in downward engagement with the said shoe.

8. In a seal press of the class in which an actuating lever is pivoted to an upper portion of the frame of the press for movement in the longitudinal vertical medial plane of the press, in which a roller is journaled in the lever on an axis parallel to the lever pivoting axis and projects downwardly below adjacent portions of the lever, in which a flat and approximately horizontal portion of a spring extends below the said roller, and in which the upper die of the press 50 underlies and is supported by the said spring portion; the seal press being characterized by having the upper die portion include a riser stem of rectangular section slidably fitted into and extending through a correspondingly shaped perforation in the said spring portion, by having at least the upper part of the said stem expanded to wedge the stem in that perforation; and by including a shoe extending freely above the up- 55

per end of the riser stem and having a flat upper face continually engaged by the roller, the shoe having portions thereof seated on the said spring part and presenting an upper face of considerably greater spread than the said perforation 60 and parallel to the upper face of the said spring portion.

9. A seal press in which a lever-carried roller travels on a shoe which overlies both the central portion of the upper die of the press and a vertically movable flat spring part disposed between the said die and shoe, characterized by having the die include a central and square-sectional riser stem extending upwardly through and fitting a similarly sectioned perforation in the said 10 spring part, the portion of the riser stem housed by the said perforation being radially expanded for wedging it firmly in the said perforation; the seal press being also characterized by including a shoe which has a portion thereof freely overlying the top of the said riser stem and has other shoe portions seated on the said spring portion; and which shoe presents a flat roller-engaging top parallel to the upper face of the said spring 15 part.

10. A seal press of the type in which the upper die underlies and is supported by a flat and approximately horizontal spring portion, in which the die is depressible by the downward thrust of a portion of a lever which has its vertical longitudinal plane of movement along the axis of the said die, and in which the thrust of the said lever part is transmitted to the spring through an interposed shoe; characterized by having the upper die include a riser stem of rectangular 20 section, by having the said riser stem extending at least substantially through a perforation of counterpart section formed in the said spring portion and presenting two opposite sides parallel to the said vertical plane, the said stem being expanded into the perforation so as to serve as the sole means for supporting the said upper die from the said spring portion; and also characterized by having the shoe seated upon the said spring portion and latched against movement flatwise of the spring, and by having the central portion of the shoe freely spaced from the upper portion of the said riser stem.

11. In a seal press in which the upper die underlies a spring portion which is depressible by movement of a lever and in which the die has its axis disposed in the medial longitudinal plane of the said lever, a die-supporting spring having its forward portion provided with an equal angled perforation having two opposite sides disposed parallel to and equally spaced from the said plane, the said die having an axial riser of counterpart section to the said perforation extending upwards into and expanded into the said perforation; a shoe having its central portion freely overlying the said riser and having a frame-like bottom portion seated on the spring; and a roller journaled in the lever on an axis transverse of the said plane and projecting below adjacent parts of the lever, the said shoe having a flat upper face portion parallel to the upper face of the spring and continually in upward engagement with the roller.

CHARLES PRIESMEYER.
